UNITED STATES PATENT OFFICE.

AUGUSTUS N. ALLEN, OF SCRANTON, PENNSYLVANIA.

DESIGN FOR A SMOOTHING-IRON HANDLE.

SPECIFICATION forming part of Design No. 35,078, dated September 10, 1901.

Application filed July 12, 1901. Serial No. 68,118. Term of patent 14 years.

To all whom it may concern:

Be it known that I, AUGUSTUS N. ALLEN, residing at Scranton, in the county of Lackawanna and State of Pennsylvania, have invented and produced a new and original Design for Smoothing-Iron Handles, of which the following is a specification.

My invention is in the nature of a design for handles, such as are usually adapted for detachable connection with sad or smoothing irons, and my design embodies such ornamental configuration and complete blending of its several parts, as will hereinafter be fully described, reference being had to the drawings, 5 in which—

Figure 1 is a perspective view of my complete design of handle. Fig. 2 is a vertical section of the same, taken on the line 2 2 of Fig. 1; and Fig. 3 is a section on the line 3 3 of Fig. 2 to illustrate the shape of one of the pendent or leg portions.

My new and original design embodies a representation of a body having a horizontally-extending handle 1 and pendent ends 2, that 5 terminate in flat outwardly-projecting ears 2^d. The body 1 is cylindrical in cross-section its entire length and at the ends it merges

with the ends 2, and at the merging point of the body and the ends 2 the ends 2 are rounded and made concave in horizontal section, and 30 the concavity of each end 2 gradually diminishes toward the lower ends, as does also the width of said ends, as best seen in Fig. 2. The inner edges of the ends 2 extend down at approximately right angles to the cylindrical 35 handle 1 and the said edges are turned inward to produce rounded edges, as indicated by 2^e and best illustrated in Fig. 3. The edges 2^e do not extend quite to the lower extremities of the sides 2, which have their extremities shown as bent outward at right angles to produce flat ears 2^d, which have ornate- 40 ments in the nature of openings, (indicated by d.)

What I claim is—

The design for a smoothing-iron handle, 45 substantially as herein shown and described.

In testimony whereof I affix my signature in presence of two witnesses.

AUGUSTUS N. ALLEN.
